CLAIM

the ornamental design for a tool for cleaning and polishing footgear, as shown and described.

DESCRIPTION

FIG. 1 is a top view of a tool for cleaning and polishing footgear, showing my new design.

FIG. 2 is a side view thereof;

FIG. 3 is a bottom view thereof;

FIG. 4 is a front view thereof; and,

FIG. 5 is a rear view thereof.

The broken line showing of bristles in FIGS. 2, 4, and 5 is for illustrative purposes only and forms no part of the claimed design.
